ROTARY WHEEL ADJUSTING APPARATUS FOR DRESSING A GRINDING WHEEL

Dikran Gerdjikian, 40 Austin Ave.,
Amityville, N.Y. 11701

Filed Jan. 26, 1972, Ser. No. 221,124

Term of patent 14 years

Int. Cl. D15—99

U.S. Cl. D37—1 R

FIG. 1

FIG. 2

FIG. 3

FIG. 4

FIG. 5

FIG. 6

FIG. 1 is a perspective view of a rotary wheel adjusting apparatus for dressing a grinding wheel, showing my new design;

FIG. 2 is a front elevational view thereof;

FIG. 3 is a top view thereof;

FIG. 4 is a left side view thereof;

FIG. 5 is a rear elevational view thereof; and

FIG. 6 is a bottom view thereof.

The side opposite that shown is substantially the same as the side that is shown.

I claim:

The ornamental design for a rotary wheel adjusting apparatus for dressing a grinding wheel, substantially as shown and described.
